poration of New York

Application October 4, 1946, Serial No. 133,763

Term of patent 14 years

(Cl. D26—7)

To all whom it may concern:

Be it known that I, Ray R. Hutcheson, a citizen of the United States, residing at Brooklyn, in the county of Kings and State of New York, have invented a new, original, and ornamental Design for a Grille for Electric Fans and the like, of which the following is a specification, reference being had to the accompanying drawing, forming a part thereof, wherein:

Fig. 1 is a front elevation of a grille for an electric fan showing my new design; and

Fig. 2 is a side elevation thereof.

I claim:

The ornamental design for a grille for an electric fan and the like, as shown.

RAY R. HUTCHESON.
